UNITED STATES PATENT OFFICE.

EZRA B. SMITH, OF CHICAGO, ILLINOIS, ASSIGNOR TO JERSEY SWEEPER COMPANY, OF CHICAGO, ILLINOIS, A CORPORATION OF ILLINOIS.

SWEEPER.

1,233,135.

Specification of Letters Patent. Patented July 10, 1917.

Application filed December 26, 1913. Serial No. 808,657.

To all whom it may concern:

Be it known that I, EZRA B. SMITH, a citizen of the United States, residing at Chicago, county of Cook, State of Illinois, have invented a certain new and useful Improvement in Sweepers, and declare the following to be a full, clear, and exact description of the same, such as will enable others skilled in the art to which it pertains to make and use the same, reference being had to the accompanying drawings, which form a part of this specification.

My invention relates to devices for sweeping carpets, rugs or floors and has for its object to produce a simple, powerful and reliable sweeper in which a suction is obtained by a compact, powerful spring motor driven from the handle of the device, whereby the advantages of an electrically operated sweeper and of wholly manually operated sweepers are secured without the presence of the disadvantages of either of these two types.

My invention has for a subsidiary object a simple and novel construction and arrangement which will permit the operating handle of the sweeper to stand substantially upright over the sweeper so as to take up but little space in the horizontal direction, when at rest; and, when occupying the upright position, serve as a brake or lock to stop the motor.

A further subsidiary object of my invention is to produce a simple arrangement for quickly and conveniently attaching and removing the handle of the device and for holding it securely in place when attached.

A further object of my invention is to provide a simple and novel arrangement which will permit the propelling handle to be placed in an almost horizontal position when it is desired to push the sweeper under low furniture; while at other times the depression of the handle, while still disposed at a considerable angle above the horizontal, may be utilized to depress the rear end of the sweeper and raise the front end so as to make it easy for the sweeper to pass up over the edges of rugs or the like.

A further object of my invention is to produce a simple and novel driving means for a brush coöperating with the suction device.

A further subsidiary object of my invention is to provide a simple and novel means

for securely holding the rubber tires of the sweeper on the wheels.

Viewed in one of its aspects my invention may be said to have for its object to improve, by simplifying, strengthening and making more compact, the sweeper disclosed and claimed in my prior application for sweeper, filed January 6, 1913, Serial No. 740,279.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a top plan view of a machine arranged in accordance with a preferred form of my invention, with the cover removed and the handle broken off;

Fig. 2 is a longitudinal section taken approximately on line 2—2 of Fig. 1;

Fig. 3 is a section taken approximately on line 3—3 of Fig. 2;

Fig. 4 is a section on line 4—4 of Fig. 3;

Fig. 5 is a top plan view of one of the bearings and holding devices for the handle, showing the holding means in a different position from that illustrated in Fig. 1;

Fig. 6 is a section taken approximately on line 6—6 of Fig. 5; and

Fig. 7 is a detail illustrating the brake or lock and the means for controlling it from the handle.

The frame of the machine may conveniently be made of a main casting comprising a rear cup-shaped portion, 1, and a front part, 2, serving as the housing or casing for a horizontal fan; a cover, 3, extending over the part 1 of the casting and a portion of the fan casing; and a casting, 4, lying beneath the fan casing and containing the inlet nozzle for the fan casing. In the rear portion of the main frame is a powerful coiled spring, 5, surrounding and connected at its inner end to a vertical shaft, 6, mounted at its lower end in a bearing, 7, in the frame and extending at its upper end through a bracket, 8, secured to the main frame in any suitable manner. On the shaft 6, just beneath the bracket is a ratchet wheel, 9, with which coöperates a pawl, 10, for the purpose of permitting the shaft to be rotated in the direction to wind the 105

110

spring and be held against rotation in the opposite direction. Surrounding the spring and fixed to the outer end thereof, as indicated at 11, is a drum, 12, having upon the 5 top thereof a gear wheel, 13. The gear wheel 13 meshes with a pinion, 14, on the lower end of a vertical shaft, 15, revolvably mounted in a boss, 16, of the bracket. On the upper end of the shaft 15 is a gear 10 wheel, 17. The pinion 14 and the gear wheel 17 serve as collars or shoulders to hold the shaft 15 against endwise movement.

In the fan casing is arranged a horizontal 15 fan, 18, of any suitable construction, the shaft 19 of the fan extending vertically through the top of the fan casing and through the frame 20 of a suitable gear train one member, 21, of which meshes with 20 the gear wheel 17, while another member, 22, is fixed to the fan shaft. The frame 20 of the train of gearing is preferably made in the form of a unit adapted to be attached to the top of the fan casing and be housed 25 beneath the front end of the cover.

The bracket 8 extends over the top of the motor spring and is provided between the sides of the main frame with upwardly projecting ears, 25 and 26, to which a hood-like 30 member, 27, secured to the lower end of the actuating handle, 28, of the sweeper is adapted to fit. Additional ears, 29 and 30, project upwardly from the bracket between the ears 25 and 26 and the adjacent walls 35 of the main frame. The handle is secured in place by means of horizontal trunnions, 31 and 32, mounted in the two pairs of ears 25 and 29, and 26 and 30, the inner ends of the trunnions being adapted to engage with 40 suitable sockets in the member 27 of the handle, thus securing the handle to the frame and permitting it to swing about a horizontal axis. In order that the handle may be quickly attached or detached, I 45 make the trunnions slidable in the lengthwise direction so that they may be retracted far enough to clear the member 27 on the handle and thus permit the handle to be lifted out. In order to lock the trunnions 50 in their working positions and permit them to be easily shifted from one position to another, I provide each trunnion with an elongated rod, 33, projecting at right angles through the same and of a length to 55 overlie the top edge of the rear portion 34 of the main frame when in a horizontal position. The member 34 is provided with notches, 35, in position to receive the rods 33 when the trunnions are in their working 60 positions, and lock the trunnions against accidental displacement. The short ends of the rods 33 are adapted to lie in notches, 36, in walls, 37, connecting each pair of ears and thus serve as a further lock for the 65 trunnions when the latter are in their work-

ing positions. The walls 37 are so shaped and so spaced with respect to the trunnions that when the rods 33 are swung into vertical positions, the short ends thereof are clear of the walls, permitting the trunnions to be moved into the handle-releasing positions by means of the rods. 70

The handle 28, of the sweeper, is made tubular and extending lengthwise there-through is a rod, 39, having on its upper 75 end a bevel gear, 40, and on its lower end a universal gear, 41. Upon the upper end of the handle is secured a hollow box-like casting, 42, having a grip, 43. Extending transversely into the casting 42 in proximity to the gear 40 is the shaft, 44, of a crank, 45, the shaft having a bevel pin, 46, meshing with the gear 40. By turning the crank 45, the shaft 39 may be rotated. The gear 41 meshes with a complementary gear, 47, fixed upon the upper end of the spring shaft 6. The gears 41 and 47 are of the type which permits the handle of the machine to lie anywhere between a horizontal position and an approximately upright position as 80 indicated in dotted lines in Fig. 2, preserving the driving connection, at all times, between the operating shaft and the spring shaft. 85

The handle of the machine extends 90 through a slot, 48, in the cover 3 and when swung forwardly slightly beyond an upright position, the front wall of the slot may be made to serve as a stop, so that the handle will remain in its approximately upright position. When the handle is swung back so as to lie slightly in rear of an upright position, it tends to drop down into a horizontal position. It is desirable that the handle be so arranged that it may occupy a 95 substantially horizontal position, at times, in order to permit the sweeper to be pushed underneath beds or other pieces of furniture raised above the floor. However, it is also desirable to make it possible to use the 100 handle to tilt the sweeper so as to raise its front end and permit it to pass readily up over the edge of a rug or the like. I have therefore mounted upon the rear wall, 34, of the main frame a swinging dog, 49, which 105 registers with the slot, 48, in the cover and which, in one position, engages with the under side of the handle while the handle is still at a convenient angle, while in another position it leaves the handle free to 110 assume a horizontal position. The dog consists of a simple member lying above the upper edge of the wall 34 and hinged to the wall by means of a pin, 50, passing through suitable ears, 51, extending upwardly from 115 the wall. On the inner side of the dog is a depending nose, 52, so positioned that it will engage with the interior of the wall 34 when the dog lies within the confines of the cover and occupies an approximately up- 120

right position as shown in Fig. 2. In this position a depression of the handle until it engages the dog serves to tilt the sweeper and raise its front end. When it is desired to lower the handle into a horizontal position without tilting the sweeper, the upper end of the dog is swung outwardly through the slot in the cover so as to offer no obstruction to the downward movement of the handle.

It will be seen that by turning the crank on the handle of the machine the motor spring is wound up and the spring in turn drives the fan through the gear train, the fan revolving at a high speed sufficient to produce a considerable suction. The spring is preferably made long as well as powerful so that the fan will run at an effective speed for a considerable time after the spring has been wound up. It may therefore happen that the work of the machine will be completed while there is considerable power stored in the spring, or it may be desired to stop work for a time while this condition exists. It is therefore desirable that the fan be stopped whenever the machine is stopped so that the power stored up in the spring will not be wasted. To this end I have provided a brake, 53, adapted to engage one of the gears, 54, of the train between the motor spring and the fan, the brake having an actuating arm, 55, extending across the bracket, 8, beneath the member 27 on the lower end of the handle of the machine. The member 55 has a slot, 56, extending lengthwise therein at its rear end and the member 27 has a depending ear, 57, which is adapted to enter the slot. The parts are so proportioned that normally the ear 57 simply plays in the slot without influencing the brake; while, when the handle is raised in its upright position, the ear 57 engages the rear bounding wall of the slot and draws the brake actuating member 55 rearwardly so as to bring the brake into operative relation to the gear 54. The slot, 48, in the cover is preferably made long enough, when the brake is used, to allow the handle to be supported in its approximately upright position by the brake instead of by the cover. With this arrangement, whenever the handle of the machine is placed in an upright position the motor spring is locked against unwinding and there is no loss of power due to unwinding of the spring while the machine is at rest. This locking of the spring while under tension has another advantage. In all sweepers there is apt to be some loose dust which may drop upon the floor whenever the sweeper is grasped and moved from a position of rest. In the present arrangement the fan begins to operate as soon as the handle is lowered from its upright position and before the machine starts to move, and pro-

duces a suction which acts to prevent any loose dust from being shaken down.

The machine is supported on suitable wheels, there being rear wheels, 60, one on each side of the rear portion 1 of the main frame, and front wheels, 61, one arranged on each side of the depending member 4 at the front. The wheels may all conveniently be made of flanged metal disks provided with rubber tires, 62, lying upon the flanges. The flanges are perforated as indicated at 63 so that when the rubber tires are placed in position, the rubber enters the perforations and interlocks the tires securely with the flanges.

The parts are so proportioned that the bottom of the casting 4 is held some distance above the surface on which the supporting wheels rest. The casting is made hollow and in the front end thereof is arranged a large brush, 65, extending transversely and revoluble about a transverse axis; the brush projecting down through the open bottom of the casting far enough to touch the surface over which the machine is traveling. What may be termed the nose of the casting 4, that is the lower section just in front of the opening 66 through which the brush projects, is inclined upwardly from the opening to the front edge of the casting as indicated at 67. This permits the extreme advance end of the machine to pass over an object of considerable height as, for example a small crumpled piece of paper, instead of pushing the object ahead of it; any yielding object small enough to pass under the advance end of the machine being pressed down by the inclined under face so as to bring it into a condition to be caught by the brush and carried back into a large dust chamber, 68, behind the brush. The dust chamber 68 is provided with a comparatively wide door, 69, extending across the machine, the door being hinged, as indicated at 70, adjacent to the brush and having its rear end held up by a suitable spring, 71. From time to time, the door 69 may be opened so as to allow large dirt particles and small objects which are taken up in the cleaning operation, to be discharged. The dust chamber 68 communicates with the fan casing by means of a large opening, 72, which forms a suction inlet for the fan.

The brush is preferably driven from the front wheels of the machine because it is not necessary for the brush to operate except when the machine is moving across the floor.

In the arrangement shown, and best illustrated in Fig. 3, the brush is provided with elongated trunnions, 75 which project outwardly through openings, 76, of considerable size in the side walls of the dust chamber. The outer ends of the trunnions pass through stationary plates, 77, lying in prox-

imity to the flanges of the wheel 61 and forming with the wheels closed gear boxes. On each of the trunnions, within the corresponding gear box is fixed a suitable pinion, 78, which meshes with a driving gear, 79, fixed to the corresponding wheel and concentric therewith. As the front wheels of the machine revolve they drive the pinion 78 and therefore the brush. The brush may be held against endwise movement by means of suitable straps, 80, or blocks hollowed out on one side to receive the pinion, 78, the members 80 being secured to the stationary plates 77 and having sockets, 81, for receiving the ends of the trunnions 75. The large opening 76 and the considerable length of the trunnions between the brush and the supporting bearings, prevents the brush from becoming clogged when threads are picked up and wrapped about the trunnions. The housing of the gears 78 and 79 in a closed chamber out of close proximity with the adjacent wall of the dust chamber insures that threads and the like will not be picked up and work between the gears so as to clog them and interfere with their operation.

The trunnions 75 may of course be connected to the brush in any suitable manner. For convenience in assembling and in removing the brush from the machine I prefer, however, to connect the trunnions detachably as best illustrated in Fig. 3. In the arrangement shown, the brush has a sleeve, 82, fixed in each end thereof, each sleeve having a slot, 83, cut lengthwise therein from the outer end of the brush. Each trunnion is of a size to fit slidably into the corresponding sleeve and has projecting therefrom a pin, 84, which enters the slot 83 and holds the trunnion and the brush against relative rotary movement, while permitting the trunnion to be slipped out of the end of the brush at will.

The discharge side, 85, of the fan will of course be connected to a suitable dust-receiving bag, not shown.

While I have illustrated and described with particularity only a single preferred form of my invention, I do not desire to be limited to the exact structural details thus illustrated and described, but intend to cover all forms and arrangements which come within the terms employed in the definitions of my invention constituting the appended claims.

I claim:

1. In a machine of the character described, a carriage, a fan casing mounted at the front end of the carriage having an inlet, a suction fan arranged in said casing, a propelling handle for the carriage, a motor spring, a vertical shaft to which said spring is connected, a driving connection between said propelling handle and said shaft, and a train of gearing between the spring and the fan.

2. In a machine of the character described, a main frame comprising a fan casing and a housing, a motor spring arranged in said housing, a fan in said casing, gearing between said spring and said fan; a cover extending across said housing and across the gearing adjacent to the fan, a propelling handle for the machine, and a driving connection between said handle and said spring.

3. In a machine of the character described, a main frame comprising a horizontal fan casing and a spring casing lying behind the fan casing and open at the top, a fan arranged in said fan casing, a vertical shaft arranged centrally of the spring casing, a motor spring surrounding the shaft and fixed at one end thereto, a gear train arranged between the spring and the fan, a portion of the gear train resting upon the fan casing, and a cover extending over the spring casing and across the train of gearing.

4. In a machine of the character described, a main frame comprising a horizontal fan casing and a spring casing lying behind the fan casing and open at the top, a fan arranged in said fan casing, a vertical shaft arranged centrally of the spring casing, a motor spring surrounding the shaft and fixed at one end thereto, a gear train arranged between the spring and the fan, a portion of the gear train resting upon the fan casing, a cover extending over the spring casing and across the train of gearing, a propelling handle extending through said cover, and means associated with said handle for winding said spring.

In testimony whereof, I sign this specification in the presence of two witnesses.

EZRA B. SMITH.
